US00D881152S

(12) **United States Design Patent** (10) **Patent No.:** **US D881,152 S**
(45) **Date of Patent:** **** Apr. 14, 2020**

(54) **MOBILE DEVICE**

(71) Applicant: **Sonim Technologies, Inc.**, San Mateo, CA (US)

(72) Inventors: **Zhiheng Yao**, Beijing (CN); **Jeffrey Pon**, San Mateo, CA (US); **Austin Porter**, San Mateo, CA (US); **Richard Hanks**, San Mateo, CA (US)

(73) Assignee: **Sonim Technologies, Inc.**, San Mateo, CA (US)

(**) Term: **15 Years**

(21) Appl. No.: **29/644,254**

(22) Filed: **Apr. 16, 2018**

(51) LOC (12) Cl. **14-03**

(52) U.S. Cl.

USPC ..... **D14/138 AB**
